UNITED STATES PATENT OFFICE.

JOHN SHEARER, OF PRESTON, ONTARIO, CANADA, ASSIGNOR OF ONE-HALF TO GEORGE PATTINSON, OF SAME PLACE.

GIG FOR NAPPING CLOTH.

SPECIFICATION forming part of Letters Patent No. 322,983, dated July 28, 1885.

Application filed April 17, 1884. (No model.) Patented in Canada May 14, 1884, No. 19,333.

To all whom it may concern:

Be it known that I, JOHN SHEARER, of the village of Preston, in the county of Waterloo, in the province of Ontario, Canada, cloth 5 finisher, have invented certain new and useful Improvements in Gigs for Napping Cloth; and I do hereby declare that the following is a full, clear, and exact description of the same.

The invention relates to gigs for napping 10 cloth; and it consists in the peculiar combinations and the construction and arrangement of parts hereinafter more particularly described, and then pointed out in the claims.

The drawing shows a perspective view of 15 part of a gigging or napping machine with my invention applied thereto, a portion of the frame being broken away.

As my invention relates to the particular driving mechanism and the means for regulating the tension of the belt, it is not necessary to illustrate or describe the entire machine.

The cylindrical brush B, which is made of 20 any suitable material, is provided with a spindle, B', suitably journaled.

With the view of permitting the brush B to be adjusted, I fit the journal-boxes C for the spindle B' in vertical slots formed either in the main frame, or, as indicated in the drawing, in the hangers D attached to it, as shown.

E are set-screws located at the bottom of the hangers D, and utilized for the purpose of imparting a vertical adjustment to the boxes C, with the view of moving the cylindrical brush nearer to or farther from the 35 surface of the teasles A'.

F is a pulley located on and fastened to the spindle of the napping-cylinder A, and driven by any suitable power applied to the pulley 40 F' secured to said spindle.

G and H are two small pulleys journaled in the T-arm I, which is pivoted on the main frame of the machine, as indicated.

J is a small pulley on the spindle B' of the 45 cylindrical brush B.

K is an endless belt passing around the pulleys F, G, H, and J, as shown. As these three latter pulleys are much smaller than the pulley F, the speed of the cylindrical brush B 50 would be much greater than the speed of the napping-cylinder A, and as the belt K is car-

ried around the pulleys G, H, and J, so as to make the cylindrical brush revolve in the opposite direction to that in which the napping-cylinder revolves, the surface of the cylindrical brush B and teasles A', which are fixed to the surface of the napping-cylinder A, will move in the same direction. Consequently, while the greater speed of the cylindrical brush, acting on the teasles, will thoroughly 55 cleanse them of any flock which they may have gathered from the cloth, the revolving brush will in no way injure the teasles, which it might were it caused to revolve so that the surface of the brush and teasles in 60 contact with each other traveled in opposite directions.

The object of pivoting the arm I, which carries the small pulleys G and H, is to provide an easy method of tightening the belt K, as 70 it will be seen that it is merely necessary to move the arm I on its pivot in order to tighten or loosen the belt, and as means for holding it at any desired point can readily be provided, the belt can always be held tight, and it 75 also allows the adjustment of the cylindrical brush B without interfering with the length of the belt.

In order to show a means whereby the T-arm I may be adjusted, I provide the same 80 with a set screw, I', passing through the arm and bearing on a projection, i, on the main frame. Thus when the screw is turned in one direction, the arm will be forced away from the projection i, thereby tightening the belt, 85 whereas if turned in a reverse direction the arm will approach the projection, thereby permitting a slackening of the belt K.

By my arrangement of pulleys I am enabled to drive the napping and brush cylinders in a 90 reverse direction, the latter at a higher rate of speed, with a single belt connecting the two, as the power is applied directly to one of the cylinders, thereby dispensing with the pulley-shaft and extra belt commonly employed between the two cylinders in this class of machinery where the brush and napping cylinders revolve reversely, the former at a higher rate of speed than the latter.

On referring to the drawing it will be seen 95 that the belt K, after passing over the pulley F, and the pulleys G and H, attached to the

arm I, has a return fold between the latter pulleys the bight of which embraces the pulley J, thereby causing a greater frictional contact between said belt and pulley J than 5 would occur if the belt passed direct from the pulley F onto the pulley J, as in such case, owing to the great difference in diameters of the two pulleys and their short distance apart, there would be but little contact between the 10 belt and pulley J.

What I claim as new is—

1. The napping-cylinder A, provided with teasles A', and the cylindrical brush B, bearings therefor working in the slotted hangers 15 D of the main frame, and the set-screws E, for adjusting said bearings, in combination with the pulleys F J, secured, respectively, to the shafts of the cylinders A B, the pulleys G H, the belt K, and means for adjusting the pulleys G H, whereby the same tension of belt 20

may be preserved on the adjustment of the cylinder B, substantially as described.

2. The napping-cylinder A and the brush-cylinder B oppositely revolved, and the pulleys F J, secured, respectively, to their shafts, 25 in combination with the pulleys G H, located at a distance from the pulley F in line with and beyond the range of pulley J, and the belt K, passing over the pulleys F and G H, and returning on itself between the two latter pulleys, the bight of which embraces the pulley J, as and for the purpose set forth.

3. The belt K and pulleys F, G, H, and J, in combination with the T-arm I, carrying the pulleys G and H, and the main frame, substantially as and for the purpose specified. 30

JOHN SHEARER.

In presence of—

CHARLES C. BALDWIN,
W. J. GRAHAME.
